UNITED STATES PATENT OFFICE

JOHN CROSHAW WILSON, OF NANPANTAN, ENGLAND

APPARATUS FOR CLEANSING GOLF AND OTHER BALLS

Application filed August 21, 1928, Serial No. 300,999, and in Great Britain September 17, 1927.

This invention comprises improvements in apparatus for cleansing golf and other balls, the object of the invention being to provide means for automatically cleansing such 5 balls in a very efficient and expeditious manner.

According to the present invention an apparatus is provided embodying one or more travelling bands or belts adapted to convey 10 the balls through a receptacle containing cleansing fluid in combination with one or more brush members adapted to scrub said balls while travelling.

The invention also includes means for 15 transmitting reciprocatory motion to the brush or brushes, means for feeding the balls singly to the fluid receptacle and traversing same singly in succession through the apparatus and means for wiping and/or drying 20 the balls subsequent to their passage through the cleansing fluid and to the scrubbing thereof.

For the purpose of more fully describing 25 the nature of this invention reference will now be made to the accompanying drawings, wherein:—

Figure 1 is a side elevational view of apparatus in accordance with the present invention showing one side wall of the enclosing 30 casing removed.

Figure 2 is a side elevational view looking at the opposite side of the apparatus.

Figure 3 illustrates the apparatus in sectional side elevation.

Figure 4 is a cross section on line A—A of Figure 2.

Figure 5 shows in side elevation a modified form of ball feed.

Figure 6 is a plan view of Figure 5.

In a convenient method of carrying out 40 the invention, within a casing 1 of any suitable design is provided a receptacle 2 for water or other cleansing fluid, which receptacle may be formed by dividing off a portion 45 of the casing interior by an inclined plate 3. Extending down into this receptacle 2 is a rubber or like flexible endless travelling band 4 working over two end pulleys or rollers 5, 6, the uppermost pulley 50 5 being comparatively large and being fixed

upon a cross spindle 7 which constitutes the drive shaft of the apparatus.

The spindles of the pulleys 5, 6 are rotatably mounted within bearings provided in a suitable metal frame 8 which is removably fitted within the casing 1, said frame carrying the major part of the apparatus in a self contained manner. 55

On this frame 8 are provided a pair of spaced arms 9 carrying a rotatable cross spindle 10 on which is mounted a roller 11 of solid wood or the like, said roller being located above the water receptacle and pressing lightly down upon the outer face of the travelling band 4 on that side thereof which travels downward into said water receptacle. The circumference of the roller 11 is formed with a cup-shaped recess 12 large enough to accommodate one golf ball, and carried by the aforesaid frame arms 9 above this roller is a ball feed tube or chute 13 terminating at its upper end in a funnel 14. 60

The balls to be cleaned are fed into the apparatus down the tube 13, and as the roller 11 rotated by frictional contact with the band 4, said balls are received singly within the recess 12, carried round therein by the roller and fed singly on to the band, a shield 15 around the roller serving to retain the ball in the recess while being carried round. 70

The balls received on the band 4 are caused by the motion of said band to travel down into the fluid receptacle on the upper side of the band and up again on the opposite or underside of said band in the direction 85 indicated by arrows in Figure 3, the balls being maintained upon the band by guide wires 16 or equivalent members spaced the requisite distance from the ball bearing face of said band and extending over the length 90 of the band adapted to be traversed by the balls. These guide wires 16 being stationary cause the balls, which are pressed against same during their travel, to have a continuous backward rolling or rotary motion imparted thereto. 95

On the underside of the band 4, i. e., on that side which functions to convey the balls upward out of the water receptacle, are a plurality of brushes to which reciprocatory 100

motion is imparted, said brushes serving to scrub the balls moved by the band.

Advantageously three brushes or rows of brushes are installed, one brush 17 or row of brushes being mounted parallel or approximately parallel with the band 4 with the bristles projecting at right angles thereto so that the balls being conveyed are pressed between the band and bristles. The remaining two brushes or rows of brushes 18 are mounted one at each side of the band so that the bristles project inwardly immediately beneath the band towards the centre of the width thereof, said side brushes 18 coating with the balls at each side thereof.

In a convenient arrangement the stock of the brush 17 (which brush is preferably wider than the side brushes 18) is detachably secured to a slide 19 adapted to slide between fixed cross spindles 20 or the like carried by the frame 8 and angle lugs 21, reciprocatory motion being imparted to said slide 19 and brush 17 thereon by a connecting rod or link 22 from a small crank 23 on a cross spindle 24, to which spindle rotary motion is transmitted from the drive shaft 7 through gear 25 on said shaft meshing with a comparatively small gear 26 on said crank spindle 24.

The stocks of the two side brushes 18 are also detachably secured to slides 27, each slide being carried by angle brackets 28 adapted to slide along the side bars of the frame 8, and also by an inverted U shaped bracket 29 which extends across said frame 8 and connects both side brushes for simultaneous motion. The reciprocation of these side brushes 18 is effected through link 30 from the aforesaid crank spindle 24, the small gear 26 functioning as a disc crank for this purpose.

The crank pin for the connecting link 22 appertaining to brush 17 is advanced relatively to that for the link 30 appertaining to brushes 18 preferably to the extent of 180°, and in this way the centre brush 17 is moved in a direction opposite to that of the side brushes, and the balls traversed between the brushes are effectively scrubbed thereby.

After leaving the brushes, the balls are delivered into the upper inclined or funnel shaped mouth 31 of a vertically or substantially vertically disposed channel member 32 with which is associated a second flexible endless travelling band 33. The channel 32, which is conveniently fixed in a detachable manner to the aforesaid frame 8 by a pair of bolts 34, has an internal lining of textile material such as towelling, and the balls while travelling down within the channel are pressed by the band 33 on to said material so as to effect a wiping and/or drying of said balls.

The upper end spindle 35 of the travelling band 33 is rotatably mounted in slotted cranked portions of the frame 8, the lower

end spindle 36 being received in slots formed in upstanding bracket portions 37 suitably secured to the base of the outer casing 1, the two band spindles together with rollers carried thereby being readily removed from their bearings when desired. The band 33 is driven from the drive shaft 7 by belt 38 passing over pulley 39 on said shaft and pulley 40 on belt spindle 35.

After traversing the channel 32 the balls are delivered through an opening in the casing 1 on to a platform 41 or to any suitable receptacle exterior of the casing.

An opening 42 closed by screw cap or the like may be provided at the bottom of the fluid receptacle for draining same, or alternatively a drain cock may be provided.

The apparatus is fitted within the casing in such a manner that same can be readily removed therefrom and dismantled for cleaning or other purposes.

The operation of the apparatus is preferably operated manually by a crank handle 43 detachably secured to an extension of the drive shaft outside the casing, but it will be appreciated that other power may be utilized for operating the apparatus.

In a modified arrangement the rotary ball feeder 11 may be dispensed with and the feed tube 13 extended down to a position just above the band 4. Secured to one of the bars 9 carrying the tube 13 is a double crank bracket 44 within apertures in the two lateral arms of which are slidably fitted stiff wire or like members 45, said wires being spaced parallel and extending at their one end one at each side of the gear wheel 25 on the drive shaft of the machine. The opposite end portions of the wires 45 are bent over to the rear of the feed tube 13 and again bent back at their extremities to provide finger elements 45a which project into the tube 13 through holes therein.

On each wire 45 is a coiled spring 46 bearing at one end on one arm of the bracket 44 and at the other end on a pin, collar or the like 47 on the wire, said springs serving to press the wires so that the end finger portions 45a project well into the tube 13.

On each side face of the gear wheel 25 near its periphery is a small cam 48, located at diametrically opposite positions, and in operation, as the gear 25 rotates, the two cams 48 coat successively upon the two wires 45 so as alternately to slide same against their springs. By this means the two fingers 45 are alternately withdrawn from and projected into the tube 13, and in doing so, a bell which is retained between the two fingers is first released to fall on to the band 4 and subsequently another ball is permitted to enter between said fingers, it being understood that sufficient space exists between the two fingers for receiving a single ball.

In this modified arrangement the second

endless band 33 is preferably driven from the gear 25 through a small gear wheel 49 which meshes therewith and with a further small gear on the one end spindle 35 of the said band 33.

5 I claim:—

1. Apparatus for cleansing golf and other balls comprising conveying means for moving the balls through the apparatus, guide wires 10 for retaining the balls on the conveying means, a plurality of brushes operating to scrub the balls while being moved, and means for imparting reciprocating movement to said brushes in opposite directions to each 15 other.
2. Apparatus for cleansing golf and other balls comprising a cleansing fluid receptacle, conveying means for moving balls through the receptacle, means for retaining the balls 20 on said conveying means while being moved thereby, a plurality of brush members operating to scrub the balls, and means for imparting reciprocating movement to said brush members in opposite directions to each other.
- 25 3. Apparatus for cleansing golf and other balls comprising a cleansing fluid receptacle, an endless belt conveyor for passing the balls through the cleansing fluid receptacle, ball retaining means situated at a parallel spaced 30 distance from the conveying means, a plurality of brush members serving to scrub the balls while passing through the cleansing fluid receptacle, and means for operating said brushes in opposite directions to each other.
- 35 4. Apparatus for cleansing golf and other balls comprising a cleansing fluid receptacle, an endless belt conveyor for passing the balls through the cleansing fluid receptacle, stationary means for frictionally retaining the 40 balls on the conveyor and to impart a continuous backward rotary motion to said balls, said conveyor serving to press the balls against a plurality of reciprocating brushes, and means for operating said conveyor means.

45 JOHN CROSHAW WILSON.
